UNITED STATES PATENT OFFICE.

WILTON S. SCHUYLER, OF CINCINNATI, OHIO.

ACCELERATOR FOR COMBUSTION ENGINES.

Application filed June 13, 1923. Serial No. 645,043.

To all whom it may concern:

Be it known that I, WILTON S. SCHUYLER, a citizen of the United States of America, and a resident of Cincinnati, in the county 5 of Hamilton and State of Ohio, have invented a new and useful Improvement in an Accelerator for Combustion Engines, of which the following is a specification.

An object of my invention is to provide a 10 simple and efficient accelerator that may be applied to motor vehicles.

Another object of my invention is to provide a device wherein the action of the ordinary hand throttle is in no wise affected 15 by the attachment of a device embodying my invention to the carbureter.

Another object of my invention is to provide a device that may be readily mounted upon motor vehicles and that will provide 20 a firm and substantial support to the operator's foot.

These and other objects are attained by the means described herein, and disclosed in the accompanying drawings, in which:

25 Fig. 1 is a fragmental perspective view of a motor vehicle having mounted on it a device embodying my invention.

Fig. 2 is a side elevation of a foot lever forming a detail of my invention.

30 Fig. 3 is an end view of the device shown in Fig. 2.

Fig. 4 is a plan view of a plate and actuating means associated therewith, all of which form details of my invention.

35 Fig. 5 is a side elevation of the device shown in Fig. 4.

Fig. 6 is an elevation of a carbureter control arm having mounted on it a device embodying my invention.

40 I have disclosed my invention as applied to a Ford automobile. The free end 8 of the carbureter arm 7 is in the ordinary Ford structure connected with a hand throttle by means of a suitable connection. It is cus-

45 tomary to provide the end 8 of the carbureter arm with a bore in which such throttle end engages. In applying my device the throttle connection is disconnected from the arm 7 and the plate 9 is secured upon the arm 7 by passing a suitable bolt

50 11 through a bore provided therefor in the plate 9 and lodging in the bore in the end 8 of the arm 7. The plate 9 has formed on it depending lugs 12 and 13 that straddle the

55 arm 7. From the foregoing it will be apparent that if the plate 9 is moved in the

direction in which the arm 7 is capable of movement that the plate 9 and the arm will move as a unit. The plate has mounted on it a bar 14 that is pivoted at 15 upon the plate 9 and is provided at its free end with an aperture 16 for the reception of the throttle rod connector that was removed from the bore in the end 8 of the carbureter arm 7. A reciprocating pin 17 has its one end 18 pivotally mounted upon a stud 19 carried by the bar 14. The plate has an upwardly extending flange 20 provided with an aperture through which the pin 17 may be reciprocated. A washer 21 is mounted on the pin 17 adjacent its pivotally mounted end, and a spring 22 mounted on the pin 17 has its opposite ends in abutment upon the washer 21 and the flange 20. A lug 23 struck upwardly from the plate 9 limits the movement of the bar 14 under the influence of the spring 22. The plate is provided with an aperture 24 for the reception of one end of a connecting rod 25 extending forwardly from the foot pedal 26. The rear end of the connecting rod 25 has a sliding pivotal mounting upon a pin 27 pivotally mounted at the lower end 28 of an arm 29 fixedly carried at one end of a crank shaft 30 extending transversely of the foot lever frame 31. The crank shaft 30 carries a crank 32 that is pivotally connected to the lower end of a reciprocating plunger 33 carried by a lateral extension 34 formed on the frame 31. A suitable head 35 formed on the upper end of the plunger 33 is adapted to be engaged by an operator's foot and to be moved downwardly through an opening in the lateral extension 34 through which the plunger reciprocally extends, and against the yielding resistance of the spring 36 having its opposite ends in abutment on the lateral extension and the head 35. A laterally extending foot rest 37 extends upwardly and sidewardly on the frame and is adapted to be contacted by an operator's foot whereby to give a substantial and rigid support to the operator's foot adjacent the head of the plunger. The frame 31 has formed on it rearwardly extending lugs 38 and 39. The lug 38 is adapted to be mounted directly upon the housing 40 of the vehicle transmission and lug 39 has pivotally mounted on it a link 41, the link being adapted to have its one end secured upon the transmission housing 40. When the device is mounted on a vehicle the floor boards of

the vehicle are disposed substantially at the upper end of the lateral extension 34 thereby protecting the transversely extending crank shaft 30 and the parts associated therewith from mal-treatment.

In the operation of my device the downward pressure of an operator's foot on the plunger serves to rotatably actuate the crank shaft 30 which motion is utilized for pulling the connecting rod 25 rearwardly. The forward end of the connecting rod, being connected with the plate 9 serves to move the plate in a counterclockwise direction, see Figs. 1 and 4. During the movement 10 of the plate under the influence of the foot pedal, the bar 14 connected with the handle throttle remains stationary because of its connection with the hand throttle. The spring 22 yieldingly resists movement of 15 the plate 9. The spring 36 yieldingly resists movement of the foot pedal. When the hand throttle is actuated the engagement of the bar 14 upon the lug 23 serves to transmit motion from the bar to the plate. At 20 such times the connecting rod 25 is free to slide through the pin 27 thereby avoiding binding of any of the foot pedal parts and the connecting rod 25. It should be noted that operation of the carbureter by either 25 the foot accelerator or the hand throttle will not actuate the other carbureter control means. The foot pedal structure, comprising the frame 31 gives a solid and substantial support for the operator's foot and pre- 30 cludes pulsating of the carbureter valve because of any vibration of the vehicle body.

What I claim is:

1. In a device of the class described the combination of a plate, a carbureter arm, 40 means for mounting the plate on the arm for movement therewith, a bar carried by the plate, means for transmitting movement from the bar to the plate when the bar is actuated in a given direction, and yielding 45 means permitting independent movement of the plate.

2. In a device of the class described the combination of a carbureter arm, a plate carrying projecting lugs and a flange, and 50 having an aperture formed in the flange, a pair of lugs being adapted to straddle the carbureter arm, means for securing the plate upon the carbureter arm, a bar pivotally mounted on the plate, a pin extending reciprocally through the aperture in the flange and having a pivotal mounting upon the bar, a spring operative 55 upon the pin for retaining the bar in yielding engagement upon a third lug carried by the plate, and independent means connected with the bar and the plate for selectively actuating the plate and the bar.

3. The combination of a carbureter arm having an aperture in its free end, a plate 65 carrying a pair of depending lugs for strad-

dling the arm and having an aperature for registration with the aperture in the carbureter arm, a bolt extending through the apertures in the plate and the carbureter arm, a flange and a lug extending upwardly 70 from the plate on the side opposite to the pair of lugs first mentioned, the flange having an aperture therein, a bar pivotally mounted at one of its ends upon the plate and having an aperture in its other end for the reception of a connecting rod and adapted to engage the third mentioned lug, a pin having one of its ends pivotally mounted upon the bar intermediate the ends of the bar, the pin having its other end extending 75 through the aperture in the flange, a spring operative upon the pin for yieldingly retaining the bar in engagement upon the third mentioned lug, and a connecting rod carried by the plate for actuating the plate 80 independent of the bar.

4. In a foot pedal of the class described the combination of a fixed frame having an upwardly extending fixed foot rest and a lateral extension, a plunger reciprocally mounted upon the lateral extension, a crank shaft rotatably supported by the frame and extending transversely of the frame, an arm at one end of the crank shaft, a crank at the other end of the shaft having a pivotal 90 mounting upon the plunger, the arm being arranged for pivotal connection with a connector rod, the foot rest providing a support for an operator's foot when operative upon the plunger.

5. A foot lever control of the class described comprising a frame having a pair of lugs, a lateral extension and a foot rest extending therefrom, a crank shaft carried by the frame for oscillatory movement, a crank carried by the shaft, a plunger reciprocally extending through the lateral extension and disposed at one side of the foot rest, the lower end of the plunger having a pivotal mounting upon the crank for converting a reciprocating motion of the plunger into an oscillatory motion of the crank shaft, means yieldingly resisting movement of the plunger, a connecting rod, means for converting the oscillatory motion of the crank shaft 105 into a reciprocating motion of the connecting rod, the connecting rod having a sliding pivotal mounting upon the last mentioned means, the lugs extending from the frame 110 being capable of mounting upon the transmission housing of a vehicle.

6. A foot lever control of the class described comprising a frame having a pair of lugs, a lateral extension and a foot rest extending therefrom, a crank shaft carried by the frame for oscillatory movement, a crank carried by the shaft, a plunger extending reciprocally through the lateral extension and disposed at one side of the foot rest, the lower end of the plunger having a 120

pivotal mounting upon the crank for converting a reciprocating motion of the plunger into an oscillatory motion of the crank shaft, means yieldingly resisting movement of the plunger, a connecting rod, and means for converting the oscillatory motion of the crank shaft into a reciprocating motion of

the connecting rod, the lugs extending from the frame being capable of mounting upon the transmission housing of a vehicle. ¹⁰
In testimony whereof, I have hereunto subscribed my name this 5th day of June, 1923.

WILTON S. SCHUYLER.
